(57) **CLAIM**

The ornamental design for a hose clip, as shown and described.

DESCRIPTION

FIG. 1 is a top front perspective view of the hose clip; FIG. 2 is a front elevation view thereof, with the rear elevation view being a mirror image thereof;

FIG. 3 is a right elevation view thereof, with the left elevation view being a mirror image thereof;

FIG. 4 is a top elevation view thereof; and,

FIG. 5 is a bottom elevation view thereof.

The broken lines shown in the drawings illustrate portions of the hose clip that form no part of the claimed design.
